Specification of Letters Patent. Patented Aug. 8, 1911.

Application filed October 17, 1910. Serial No. 587,806.

To all whom it may concern:

Be it known that I, FREDRIK LJUNGSTRÖM, engineer, a citizen of Sweden, and a subject of the King of Sweden, and resident of 2⁴ Drottningholmsvägen, Stockholm, in the Kingdom of Sweden, have invented certain new and useful Improvements in Gas or Steam Turbines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to gas or steam turbines and particularly to turbines of the radial flow type wherein concentric packing rings are provided on the sides of the turbine wheel, and has for its object to so mount these rings that leakage will be reduced to a minimum.

In gas and steam turbines the hot motive fluid flows through a number of relatively light and close-fitting rings which are heated more rapidly than the heavier parts carrying the same, this premature heating of the rings, owing to their construction and arrangement, causing the individual ring bodies to expand unevenly and more rapidly than the heavier parts to which they are secured, whereby more or less warping and consequent binding of the rings results. In order to overcome these defects many methods are at present employed, certain ones of which consist in providing relatively large spaces between the rings, this arrangement resulting in excessive leakage and consequent low efficiency of the turbine.

The present invention has for its object to provide an arrangement of packing rings, whereby uniform and free expansion thereof will be permitted independently of the parts carrying the same, and at the same time reducing leakage to a minimum and increasing the efficiency of the turbine. To this end I provide thin drum-shaped connections between the rings and the parts directly carrying the same, the structure being such that by this arrangement the heat is confined in the rings or substantially so, whereby the possibility of a sudden transference of heat to the ring-carrying parts

will be reduced. Furthermore with this construction whether the rings are of uniform diameters and arranged in a group or of different diameters and arranged to present a tapering surface will be immaterial in so far as uniformly heating them is concerned. I have found that this means for confining the heat may also be used to connect the vanes to their usual supports, thus doing away with the old method of inserting the ends of the vanes directly into the vane carrying parts.

The novel features of the invention will be apparent from the following detailed description taken in connection with the accompanying drawing.

In the drawing: Figure 1 shows in section the upper part of a turbine provided with packing rings according to my invention. Figs. 2 to 4 inclusive show modified details of the packing rings in section. Fig. 5 shows a plan view of parts *a* and *k* of Fig. 4 in plan.

In the drawings, *a* designates the turbine casing, *b* the gas or steam inlet, *c* the turbine wheel, *d* the turbine shaft, *e* the fixed vane rings and *f* the rotating vane rings.

g indicates the packing rings and *h* and *i* the members carrying the rings and fixed respectively on the turbine wheel *c* and the turbine casing *a*.

k designates the annular or drum-shaped connections arranged between the turbine casing and the wheel *c* on one side of the latter and also designates the connection between the members *h* and *i* carrying the packing rings *g* on the opposite side of the wheel *c*. The connections are secured by means of wedge rings *l*.

The motive fluid may flow into the packing rings through the steam channels *o*.

The drum-shaped connections may be made as shown in Figs. 1 to 3 by the turning down of thicker rings, or they may be made separate as shown in Fig. 4, and then secured in any suitable manner as, for instance, by means of rings *r* to the turbine casing or the turbine wheel. They may also, as shown in Fig. 5, be provided with axial slits *s*, thereby forming a number of axial tongues arranged close to each other.

Fig. 2 shows packing rings *g*, the drum-shaped parts *k'* of which are integral with the carrying members *h', i'*. The disks *h*

and i , as shown in Fig. 1, are thereby omitted and h' and i' are secured to the casing a and the turbine wheel c respectively.

Fig. 3 shows a number of vane rings e' joined in groups by means of rings p secured to the casing a by means of the parts k .

At m in Fig. 1 two adjacent rings k are fixed to the casing a by means of a single wedge ring n .

It will be seen that by means of the constructions above described which comprise a thin connection between the packing rings and the carrying parts, that the rings are free to expand and that a minimum amount of heat will be transferred through the thin connections to the carrying parts.

Having thus described my invention what I claim is:—

- 20 1. In turbines in combination, packing rings, parts carrying same and thin members joining said rings and said ring carrying parts.
2. In turbines in combination, packing

rings, parts carrying same and thin drums 25 joining the rings and said parts.

3. In turbines in combination, packing rings, parts carrying same and thin cylindrical drums joining the rings and said parts.

30

4. In turbines in combination, packing rings, divided in groups, ring carrying parts and a cylindrical drum between each group and said parts.

35

5. In turbines in combination, packing rings, parts carrying same and thin drums, being integral with the ring carrying parts and joining same with the packing rings.

6. In turbines in combination, rings, parts carrying same and thin radially slotted 40 drums between said rings and said parts.

45

In testimony, that I claim the foregoing as my invention, I have signed my name in presence of two subscribing witnesses.

FREDRIK LJUNGSTRÖM.
